ington, N.J., a corporation of New Jersey

Application September 21, 1946, Serial No. 698,584

7 Claims. (Cl. 112—60)

1

The present invention relates to machines for securing together with permanent fastenings the marginal portions of a shoe upper and sole assembled without the support of a last and for simultaneously securing to said marginal portions a welt or strip to be employed in completing the shoe. In certain respects, the invention is an improvement over that disclosed in United States Letters Patent No. 2,388,475, granted April 16, 1946, on an application of Karl A. Stritter.

In the machine of the patent referred to, temporarily attached marginal portions of a shoe upper and sole are presented to a sewing machine in divergent relationship and a platform cover strip also is directed toward the sewing point in doubled-up condition in order to prevent the free edge of the strip from interfering with the operating devices in the machine and otherwise to facilitate fastening the strip in position on the upper. The upper and sole of the shoe in the patent referred to are presented to the machine without the support of a last and, in fact, no more than a preliminary upper shaping operation has been performed before the sewing operation. In order to attach the marginal portions of the upper and sole temporarily before sewing, the upper at least is beveled and its beveled face is cemented to the sole of the shoe with the edges of the parts in accurate register. When the upper and sole are thus temporarily attached, they assume roughly the contour of a shoe with their portions remote from the registering edges diverging at an angle to each other, the upper being shaped to form the angle with the more rigid flat sole along the portions of the sole and upper bordering the registering edges.

In applying the strip, the parts are clamped together and the strip forced into conformity with the curvature of the upper at the point of sewing operations. Forcing the strip into conformity with the curvature of the upper, may tend to deflect the strip out of parallelism with the line of the seam along the curved portions of the upper, particularly about the abruptly curving toe portion, producing irregular results where the shoe parts are composed of heavy relatively inflexible stock.

An object of the present invention is to provide a machine which will operate successfully in sewing together a shoe upper and sole while unsupported by a last and simultaneously for securing a welt or a platform cover strip to the shoe parts without deflecting the strip at the sewing point of the machine from a uniformly flattened condition.

2

In the illustrated embodiment of the present invention, flexure of the welt or strip at the sewing point is avoided by arranging the shoe clamping devices in such a way that the sole and upper are bent along those portions bordering the registering edges while the surface of the upper engaged by the strip at the sewing point is forced into a flattened condition, avoiding the necessity of deflecting the strip itself while fastening the parts. Preferably, a guide is provided in advance of the operating point to hold one edge of the strip in proper relation to the sewing point as the operation progresses. While the construction illustrated is of particular advantage when used in a sewing machine, improved results also are obtainable with shoe engaging and clamping devices in machines for fastening a welt or similar strip to shoe parts by fastenings other than stitches.

Other features of the invention consist in the devices, combinations and arrangements of parts hereinafter described and claimed the advantages of which will readily be understood from the following description taken in connection with the accompanying drawings, in which

Fig. 1 is view in side elevation of a sewing machine embodying the features of the present invention;

Fig. 2 is a detail view in front elevation of a mounting for the work supporting horn in the machine of Fig. 1;

Fig. 3 is a sectional plan view taken along the line III—III of Fig. 2;

Fig. 4 is a detail view in left side elevation of the horn mounting of Fig. 2;

Fig. 5 is a detail view on an enlarged scale of the work clamping and guiding devices of the machine taken in section through the sewing point of the machine with the parts constructed to apply an ordinary welt to a shoe;

Fig. 6 is a similar view of the same parts while operating upon a shoe including a sole edge binding strip;

Fig. 7 is a similar view illustrating the manner of attaching an inverted welt to a shoe in the machine;

Fig. 8 is a sectional plan view of the parts illustrated in Fig. 5 taken along the line VIII—VIII;

Fig. 9 is a detail plan view of the welt strip guide on the machine; and

Fig. 10 is a sectional view of the guide illustrated in Fig. 9 taken along the line X—X of that figure.

The machine illustrated in the drawings operates to secure a temporarily attached upper and

sole unsupported by a last to a welt or strip by means of which an outsole or similar shoe bottoming member is later secured. The shoe herein illustrated includes an upper 12, a sole 14, shown as an insole, of somewhat thicker and more inflexible stock than the upper 12, temporarily attached along their registering edges to each other by cement. In order to facilitate cement attachment, the marginal portions of the upper are beveled to form a feather edge, the bevel face of which provides sufficient area to form a secure cement joint between the parts. The strength of the cement bond in the joint alone is insufficient to withstand the strains which would be set up if an attempt were made to insert a supporting last so that no attempt is made to insert a last at this stage of the construction. Thus, without the support of a last, according to prior practices, the marginal portions of the upper, particularly, are deflected from the point of attachment in an irregular manner along the registering edges of the parts. The sole, being more resistant to deflection, retains a substantially flattened condition so that all of the flexure necessary to give shape to the shoe is confined to the upper. If an attempt is made to clamp the shoe parts together with a welt strip at the sewing point, under conditions of deflection assumed naturally during temporary attachment of the registering edges, difficulty will be encountered in leading a welt or other strip to the sewing point, the welt being deflected from a flattened condition at the sewing point to fit the curvatures along the outer marginal face of the upper.

To avoid difficulty in sewing a welt or cover strip to the outer marginal face of a shoe upper temporarily attached to a sole without the support of a last, the illustrated machine is provided with clamping and guiding devices which bend the sole along the marginal portion and flatten out the upper about the sewing point so that the strip as it approaches the sewing point will not be deflected but will lie in flattened condition during the insertion of stitches. After the stitches have been inserted and the parts are fed beyond the sewing point, they again assume their natural positions in which the stresses and strains in the parts are balanced but without affecting the movement and condition of the strip as it approaches the sewing point. In this way, necessity for careful observation and accurate control of the welt as it is being attached to the shoe is avoided and a comparatively simple form of guide may be employed, acting to hold one edge of the welt flatly in position as the operation progresses.

Referring more particularly to the drawings, the illustrated machine is provided with work clamping and stitch forming devices similar to those of the patent to Stritter above identified. These devices include a work support 16, a presser foot 18, a presser 20 in the form of a rotary disk mounted on a yieldingly actuated horn 22, a curved hook needle 24, a curved awl 26, the point of operations of which is indicated at 27, Fig. 8, and other stitch forming devices of similar construction and manner of operation to those in the machine of United States Letters Patent No. 1,169,909, granted February 1, 1916, on an application of Fred Ashworth.

The welt guide in the machine of Fig. 1 is arranged to direct one edge of a strip 28 forming a welt to the sewing point in overlapping relation to the edge of the upper while the other edge of the strip projects beyond the edge of the upper in the manner of an "inverted welt," so called,

according to the usual manufacture of shoes. The strip is presented to the sewing point in substantially flattened condition as illustrated in Fig. 7, the upper and sole being bent into conformity with the flattened upper surface of the welt. The sole 14 of the shoe, being stiffer than the upper, is deflected downwardly from its flattened condition by gripping teeth on the under surface of the presser foot and, to retain the shape of the shoe with an angular divergence between the sole and upper, the presser 20 located inside the shoe but outside a circle defined by a continuation of the curved needle cooperates with the presser foot 18 in bending the sole downwardly through a gradually curving arc. Beyond the sewing point, the sole again assumes its flattened condition and carries the strip into a shape conforming with that of the upper. In this way, tension and excessive strain on the bond between the temporarily attached upper and sole are avoided, the shoe parts operated upon still being in a shape generally corresponding to that of the completed shoe without producing undesirable reactions or displacement of one part or another.

The guide of the work support 16 is of conventional form, as illustrated in Fig. 1, having strip edge confining flanges. Such an arrangement is useful where the strip is a relatively narrow welt. With the use of a strip which is to be reversed upon itself or flexed at an angle to its sewed edge, as in the usual Goodyear welt shoe construction, a greater width of strip may be required so that a guide having corresponding widthwise capacity is needed. For this purpose, a guide may be employed to advantage which is similar to that disclosed in an application for United States Letters Patent Serial No. 617,349, filed September 19, 1945, in the name of George A. Miner, now Patent No. 2,416,767, granted March 4, 1947.

A strip guide having an unlimited widthwise capacity similar to that disclosed in the application just referred to is illustrated in Figs. 8, 9 and 10 of the drawings. This guide has a single edge confining abutment 30 and means for crowding and retaining one edge of the strip against the abutment including a friction wheel 32 rotating about an axis inclined at an angle to the line of the seam inserted by the machine and to the line of movement of the strip. The friction wheel is yieldingly maintained in contact with the strip by mounting it for rotation on a yoke 34 hinged at 36 to a block 38 on the lower portion of the guide, the guide proper being formed integrally with a work support 39. The yoke is perforated to receive a threaded stud 40 carrying a coil spring 42 compressed between the lower surface of the yoke and an adjustable thumb nut 44. Rotation of the wheel 32 tends to direct the strip in the direction of the arrow 46 in Fig. 8 whereas the abutment 30 causes the strip to travel in the direction of the arrow 48, the wheel sliding along the surface of the strip to enable the change in direction.

The open edge of the guide enables insertion within it of a strip 50, as in Fig. 5, or a platform cover strip 51, as in Fig. 6, without changes in construction or adjustment. With the use of the welts or strips 50 or 51, the unsecured edges thereof are deflected downwardly to some extent by the bent upper but no clamping action is exerted on the deflected portion of the strips so as to interfere with its proper presentation in flattened condition at the sewing point, the strips extending in an easy flowing curvature along the surface of the work support which may be shaped

correspondingly, as in Fig. 5. In the form of guide illustrated in Fig. 6, a work support 52 is provided having its work engaging surface cut away at 53 to insure freedom from clamping action of the horn against the upper and binding strip. The presser 20 and the horn 22 also are adjusted in location to prevent clamping engagement between the presser and the shoe parts during normal operation of the machine. The presser and horn are thus positively prevented from engaging the shoe parts at the sewing point and are also held clear from the bite of the presser foot against the work support at all times.

The location and mounting for the presser supporting horn enables the horn to swing about an axis in alignment with the sewing point and also to swing the presser outwardly away from the work support and presser foot to a position where a shoe may readily be applied or removed from the horn. To these ends, the lower end of the horn is formed with a vertical spindle portion 54 rotatably mounted in a block 55 rotatable in turn on a horizontal pin 58 clamped at its right end within a bracket 60 secured to the machine frame. Rotation of the horn about the pin 58 enables the presser to be swung outwardly from the sewing point of the machine to a convenient position for application or removal of a shoe. Inward movement of the presser toward the sewing point is limited by an adjustable set screw 62 threaded through a lug in the block 56 and engaging at its upper end an outwardly projecting arm of the bracket 60. The spindle portion 54 of the horn is held from downward movement in the block 55 by a circumferentially slotted clamp collar 64 surrounding the spindle 54 of the horn, the horn being raised sufficiently to avoid pressure by the presser against those portions of a shoe upper or welt strip between the presser and the work support. To limit rotational movement of the horn in the block 56, the slot in the clamp collar 64 receives the inner end of a removable pin 66 slidably mounted in a horizontal opening of an upstanding arm on the block 56. The pin 66 is formed with a knurled head and a grooved central portion within which is received a latching spring 68 when the pin is in operative position. The latching spring 68 is secured to the block by a screw 70 and may be flexed to disengage the groove in the pin when it is necessary to remove the horn from the block 56.

To urge the presser 20 yieldingly toward the sewing point of the machine, the pin 66 has connected to it one end of a tension spring 72 the other end of which is secured to the machine frame, the spring tending to keep the setscrew 62 on the block against the arm on the bracket 60 at all times.

For guiding the edge of a welt or strip on the work support, a gage in the form of a shoulder 74 is provided on the work engaging surface of the work support. This shoulder is located a proper distance to the rear of the point of needle operation to give the desired results and is spaced from the point of operation of the needle different distances on the work supports 39, 52 and 16 for different types of welt or strip, illustrated in Figs. 5, 6 and 7, respectively. The gages on the work supports 39 and 52 of Figs. 5 and 6, respectively, retain the edges of the strip employed therewith in substantial registry with the edges of the shoe sole and upper. The welt gage on the work support 16 of Fig. 7 retains one

edge of the welt strip in overlapping relation to the edge of the upper while the other edge of the strip projects beyond the edge of the upper in the manner of an inverted welt.

5 To guide the edges of the shoe sole and upper, a sole edge gage 76 of conventional form is provided. The sole gage is mounted on an adjustable arm 78, the position of which may be controlled by connections more fully described in 10 United States Letters Patent No. 2,003,526, granted June 4, 1935, in the name of Fred Ashworth.

The nature and scope of the invention having been indicated and a particular embodiment 15 having been described, what is claimed is:

1. A machine for uniting the marginal portions of a shoe upper and sole while unsupported by a last and for simultaneously securing a welt or strip to the outer face of the upper, having 20 fastening devices, a work support, a welt or strip guide on the work support arranged to engage and direct the strip toward the operating point of the machine, and a pressure foot arranged to engage the outer marginal face of the sole and 25 to clamp the marginal portion of the sole against the other parts on the work support, in combination with a presser located for action inside the shoe to bend the sole along a portion bordering the edges away from the upper while leaving the 30 sole free to be deflected by the clamping action of the presser foot.

2. A machine for uniting the marginal portions of a shoe upper and sole while unsupported by a last and for simultaneously securing a welt or strip to the outer face of the upper, having 35 fastening devices, a work support arranged to engage and direct the strip toward the operating point of the machine, and a presser foot arranged to engage the outer marginal face of the sole and 40 to clamp the marginal portion of the sole against the other parts on the work support, in combination with a presser located for action inside the shoe to bend the sole along a portion bordering the edges away from the upper while leaving the 45 sole free to be deflected by the clamping action of the presser foot, and a guide located in advance of the operating point to hold one edge of the strip in close proximity to the operating point as the operation progresses.

50 3. A machine for uniting the marginal portions of a shoe upper and sole while unsupported by a last and for simultaneously securing a welt or strip to the outer face of the upper, having fastening devices, a work support arranged to engage and direct the strip toward the operating 55 point of the machine, and a presser foot arranged to engage the outer marginal face of the sole and to clamp the marginal portions of all the parts against the work support, in combination with a 60 presser acting inside the shoe to bend the sole along a portion bordering the edges away from the upper while leaving the sole free to be deflected by the clamping action of the presser foot, a guide acting in advance of the operating point 65 to hold one edge of the strip in close proximity to the operating point as the operation progresses, and a gage on the work support for retaining the edge of the welt strip in substantial registry with the edges of the sole and upper.

70 4. A machine for uniting the marginal portions of a shoe upper and sole while unsupported by a last and for simultaneously securing a welt or strip to the outer face of the upper, having fastening devices, a work support arranged to engage and direct the strip toward the operating

point of the machine, and a presser foot arranged to engage the outer marginal face of the sole and to clamp the marginal portions of all parts against the work support, in combination with a presser acting inside the shoe to bend the sole along a portion bordering the edges away from the upper while leaving the sole free to be deflected by the clamping action of the presser foot, a guide acting in advance of the operating point to hold one edge of the strip in close proximity to the operating point as the operation progresses, and a gage on the work support for retaining one edge of the welt strip in overlapping relation to the edge of the upper while the other edge of the strip projects beyond the edge of the upper in the manner of an inverted welt.

5. A sewing machine for uniting the temporarily attached marginal portions of a shoe upper and sole while unsupported by a last and for simultaneously securing a welt strip to the outer face of the upper, having stitch forming devices including a curved hook needle, a work support, a welt guide on the work support arranged to engage and direct the welt strip toward the sewing point, and a presser foot arranged to engage the outer marginal face of the sole and to clamp the marginal portion of the sole against the other parts on the work support, in combination with a presser located for action inside the shoe and outside a circle defined by the curved needle to bend the sole along that portion bordering the edges away from the upper while leaving the sole free to be deflected against the presser by the clamping action of the presser foot.

6. A sewing machine for uniting the temporarily attached marginal portions of a shoe upper and sole while unsupported by a last and for simultaneously securing a welt strip to the outer face of the upper, having stitch forming devices including a needle, a work support, a welt guide on the work support arranged to engage and direct the welt strip toward the sewing point,

and a presser foot arranged to engage the outer marginal face of the sole and to clamp the sole against the portions of the other parts on the work support, in combination with a presser located for action inside the shoe to bend the sole along that portion bordering the edges away from the upper while leaving the sole free to be deflected against the presser by the clamping action of the presser foot, and a yieldingly actuated horn on which the presser is mounted for urging the presser toward the sewing point.

7. A sewing machine for uniting the temporarily attached marginal portions of a shoe upper and sole while unsupported by a last and for simultaneously securing a welt strip to the outer face of the upper, having stitch forming devices including a needle, a work support arranged to engage and direct the welt strip toward the sewing point, and a presser foot arranged to engage the outer marginal face of the sole and to clamp the marginal portions of all the parts against the work support, in combination with a presser acting inside the shoe to bend the sole along that portion bordering the edges away from the upper while leaving the sole free to be deflected against the presser by the clamping action of the presser foot, a yieldingly actuated horn on which the presser is mounted for urging the presser toward the sewing point, and an adjustable setscrew for limiting the movement of the presser toward the sewing point.
